RAILWAY TRAFFIC CONTROLLING
APPARATUS

Herbert A. Wallace, Edgewood, Pa., assignor to
The Union Switch & Signal Company, Swiss-
vale, Pa., a corporation of Pennsylvania

Application March 12, 1932, Serial No. 598,434

9 Claims. (Cl. 246—3)

My invention relates to railway traffic controlling apparatus, and particularly to train governing apparatus adapted to be controlled from a remote point such as a train despatcher's office.

5 More specifically, my invention relates to the trackway portion of such apparatus.

I will describe one form of apparatus embodying my invention, and will then point out the novel features thereof in claims.

10 In the accompanying drawings, Figs. 1 and 2, when placed side by side, with Fig. 1 on the left, form a diagrammatic view illustrating a stretch of railway track containing a siding, with the associated trackway apparatus, embodying my invention, for giving the despatcher full control of traffic moving in either direction over the stretch of track containing the siding, without the necessity for wayside signals.

Similar reference characters refer to similar 20 parts in each of the two figures.

Referring to the drawings, the stretch of railway track is divided into sections B—C, C—F, and F—G, each provided with the usual track circuit comprising a source of current 2 and a track 25 relay designated by the reference character R with an appropriate exponent. Although I have shown source 2 as a battery, it will be understood that an alternating current source can be used instead, provided that the track circuits are 30 suitably modified. In addition, I have provided a track transformer at each end of every section for at times supplying the track with alternating current which is periodically interrupted or 35 varied at different rates or frequencies by a coding device, for the purpose of governing cab signals carried on a locomotive. For example, in section B—C, battery 2 which is connected in series with the secondary of transformer T³ supplies energy to track relay R³. Transformer T³ 40 is arranged to supply periodically varied alternating current to the track rails of section B—C for controlling traffic moving in the direction from B to C, whereas transformer T¹⁰ is arranged to supply periodically varied alternating 45 current to the same rails for controlling traffic moving in the reverse direction. The alternating current which is periodically interrupted or varied to govern the cab signal indications may 50 be of any suitable frequency, such as 60 or 100 cycles per second, for example.

The transformers in any given section are energized, at times, by a despatcher at office Y, so that when a locomotive enters a given section, traffic conditions being proper, alternating current periodically varied at a given frequency will

be fed to the rails from the transformer at the exit end of that section. The locomotive-carried apparatus for translating this periodically varied rail current into cab signal indications, as well as the coding device for periodically varying the alternating current, will not be described in detail as these form no part of my present invention. One form of such translating apparatus and coding device is shown and described in United States Patent No. 1,773,472 granted to 10 Paul N. Bossart on August 19, 1930, for Railway traffic controlling apparatus.

Associated with track section C—F is a siding D—E into which trains may enter over either of the manually operable railway switches WC or 15 WF. It is not necessary to provide a track battery and a track relay for the siding D—E, but I have, however, provided transformers T⁴ and T⁵ for the purpose of supplying periodically varied alternating current to the siding rails 20 under certain conditions to be explained hereinafter.

At the ends of track section C—F, I have shown phantom signals S¹, S⁵, S⁴ and S⁶. It is to be understood that in my invention I specifically 25 contemplate that no wayside signals need be used, and I have shown the above phantom signals merely to make it easier to visualize the cab signal indications in the various sections. Wherever, throughout the following description, 30 the display of signals is mentioned, it will be understood, therefore, that reference is made to cab signals and not to wayside signals. It will be understood that the cab signal indication represented by signal S¹ will be received 35 throughout approach section B—C by a train moving from left to right. Likewise, the indication represented by signal S⁴ will be received throughout main section F—C by a train moving from right to left. The indications of the remaining 40 signals illustrated are effective in a similar manner in the respective sections governed thereby.

For purposes of illustration, I shall make use of code frequencies 180, 120, and 80 interruptions or periodic variations per minute in the alternating current supplied to the rails by coding devices such as NC or NF, for producing cab signal indications corresponding to the frequency of such periodic variations. I shall use the code frequency of 180 to indicate "proceed"; the code frequency of 80 will indicate "approach"; whereas the code frequency of 120 will indicate "take siding" in the case of a train entering section B—C or G—F, and the same code frequency of 120 will be interpreted to mean "leave siding" when re- 55

ceived by a train occupying siding D—E. The absence of code will result in a "stop" indication.

It will be understood that the above code frequencies, as well as the number of codes used, 5 are merely illustrative, and other code frequencies can readily be used, and the number of codes changed to provide different or additional information by which the train may be governed, the purpose of the present disclosure being to show 10 only the essential elements of a simple operative system in order not to complicate the disclosure unnecessarily.

I propose to give the despatcher direct control 15 of those signal indications which govern traffic movements in the proximity of stations such as C and F. It will be apparent without further explanation that the despatcher can be given control of signal indications at any additional locations, for conveying any desired information to 20 a train by merely duplicating some of the control apparatus herein disclosed.

For controlling the signal indications which govern traffic in the vicinity of the left hand end of section C—F, I have provided a group of four 25 stick relays MC, SC, RC and LC, and a similar group comprising stick relays RF, LF, SF, and MF, is provided for governing traffic in the vicinity of the right hand end of section C—F. The relays of either group can be energized either singly or 30 in appropriate pairs by means of suitable code impulses originating in the despatcher's office Y, containing the despatcher's code transmitter, and transmitted therefrom over the line circuit D¹—D². These code impulses originating in the despatcher's office are not to be confused with the alternating current code frequencies which are impressed on the track rails, and which originate in the coding devices NC and NF.

Relay MC or MF, when energized, selects a 40 main line route by causing appropriate cab signal indications to be displayed in the approach track section B—C or G—F, respectively, whereas relay SC or SF selects a route over the siding D—E. Relays RC and LC, as well as RF and LF are 45 traffic direction relays and determine whether traffic is to move in the right hand or the left hand direction, respectively. The manner in which the above stick relay groups govern the cab signal indications will be explained hereinafter.

50 Each of the above stick relay groups is controlled by a group of decoding relays designated by the reference characters QC and QF, having the function of closing a pickup circuit, or opening a stick circuit, for one or more stick relays of the first 55 group upon receipt of the proper code over the line wires D¹ and D². The decoding groups QC and QF, as well as the code transmitting apparatus at the despatcher's office, are not shown in details, as such apparatus is well known in the 60 art, and any one of several systems can be used, as for example, the system shown and described in the copending application for Letters Patent of the United States, Serial No. 373,675, filed by Lloyd V. Lewis, on June 25, 1929, for Remote Controlling Apparatus. For the purpose of my present invention, it will be sufficient to state that, 65 upon the transmission of a suitable code from the despatcher's office, proper cab signal controlling devices will be actuated at any one of several possible wayside or field stations, such as station C or station F.

Both track switches WC and WF are shown occupying the normal position, for main line traffic movement, and the corresponding switch-operated circuit controllers VC and VF are also

in the normal position, in which contacts 4—5 and 7—8 are closed. As soon as either switch is moved a short distance away from the normal position, contacts 4—5 and 7—8 both open. When the switch reaches its reverse position, contacts 4—6 close, but contacts 7—8 remain open. The track circuit for section C—F includes the contacts 7—8 of each circuit controller VC and VF. It will be apparent, therefore, that if switch WF is reversed, the rail circuit of section 10 C—F will be opened and a train approaching switch WF from the left on section C—F will receive a stop indication. A similar condition will exist in the case of a train moving in the reverse direction and approaching switch WC 15 from the right on section C—F, if switch WC is reversed.

Relays KC and KF are slow acting alternating current relays capable of remaining steadily picked up when supplied with the periodically 20 carried alternating current which is fed to the track transformers for producing cab signal indications. The releasing time of relay KC or KF is sufficiently long to prevent closing of back contact 9 or opening front contacts 33 and 41 25 during the recurring intervals when the value of the periodically interrupted or varied alternating current is a minimum or zero.

The purpose served by stick relays JC and JF, and repeater relays PC and PF, will become 30 apparent from a description of typical traffic movements to be presented in detail hereinafter.

For simplicity, I shall assume that coding devices NC and NF operate continuously, supplying 35 periodically varied alternating current of code frequencies of 180, 120 and 80 variations per minute to wires 180, 120 and 80, respectively. It will be understood, however, that these coding devices can be arranged to be normally de-energized, being set into operation by the approach of a train, in the usual and well known 40 manner.

With the above preliminary explanation in mind, I shall assume that a train approaching from left to right has entered section B—C, and 45 that the despatcher wishes to instruct the train to proceed on the main line, section C—F being unoccupied. To do this, the despatcher will send out a suitable code over wires D¹ and D² which will pick up the main route stick relay MC and 50 the right hand traffic direction stick relay RC, at station C. Transformer T³ will now receive current of 180 code frequency over a circuit starting at wire 180 of coding device NC, wires 11 and 12, front contact 13 of relay PC, wire 14, front 55 contact 15 of relay MC, wire 16, front contact 17 of relay RC, back contact 18 of relay LC, wire 19, and primary winding of transformer T³ to common terminal O. Track section B—C will therefore be provided with current of 180 code frequency and the cab signal of the train will indicate "proceed at full speed", which will mean 60 "proceed on main line".

If, instead of instructing the train to proceed on the main line, the despatcher wishes to have 65 the train enter the siding D—E, he will send out a suitable code to pick up siding route stick relay SC and right hand traffic direction stick relay RC. Transformer T³, and therefore track section B—C, under this condition, will receive current 70 of 120 code frequency over a circuit starting at wire 120 of coder NC, wire 20, front contact 21 of relay SC, wire 16, front contact 17 of relay RC, back contact 18 of relay LC, and wire 19 to transformer T³, as before. The cab signal will now 75

- indicate "take siding" through track section B—C, for a train movement into siding D—E. The distance B—C should, of course, be adequate for permitting the train to come to a stop at point C.
- 5 In a similar manner, the despatcher may, at will, impress current of 80 code frequency upon track circuit B—C to cause an "approach" cab signal to be displayed, by sending out a code to pick up either one or the other of stick relays 10 MC or SC, keeping the three remaining stick relays at station C deenergized. The circuit for transformer T³ with relay MC picked up, will start at wire 80 of coder NC, wires 22 and 23, front contact 24 of relay MC, wires 25 and 26, 15 back contact 17 of relay RC, back contact 18 of relay LC and wire 19 to transformer T³. If relay SC had been picked up instead, the above circuit for transformer T³ would include wire 13 and front contact 74 of relay SC, in place of wire 20 23 and front contact 24 of relay MC.
- If the despatcher wishes to display a stop signal in section B—C, he may do this by sending out a code which will release any stick relays 25 remaining energized at station C, whereupon the circuit for transformer T³ will be opened and no code current will be fed to track circuit B—C, resulting in a stop indication.
- It will be understood that the pick-up circuits 30 for stick relays RC and LC, governed by the coding relays QC, are so arranged that it is not possible for both relays RC and LC to be picked up at the same time, this requirement being essential since these relays govern opposing traffic routes. For a similar reason, stick relays 35 MC and SC cannot both be energized at one time. Once a route is set up by picking up the proper stick relays at station C, the stick feature of these relays will cause this route to be maintained for following trains without further action by 40 the despatcher, until the despatcher sends out a deenergizing code, or until he sends out a code to set up a route inconsistent with the route then effective.
- I shall now describe the manner in which 45 traffic moving toward section B—C from the left, or toward section G—F from the right, is controlled, and this can be illustrated to best advantage by rearranging the two sheets of the drawings so that Fig. 2 occupies a position 50 to the left of Fig. 1. When arranged in this manner, the drawings illustrate an extension of the system through the single track stretch between control points such as F and C. If track section B—C is unoccupied, and relay LC is de- 55 energized, a train moving from left to right will receive a proceed signal in section G—B because transformer T¹ will be energized with current of 180 code frequency by virtue of a circuit starting at wire 189 of coder NC, wires 11 and 21, 60 back contact 28 of relay LC, wire 29, front contact 30 of track relay R³ and wire 31 to transformer T¹. Similarly, if track sections B—C and G—B are both unoccupied, a train moving from left to right in section F—G will receive a proceed signal, provided the dispatcher has caused 65 relay RF to be energized to establish the corresponding direction of traffic. The proceed signal in section F—G will be obtained because transformer T⁹ will be energized with current of 70 180 code frequency by virtue of the same circuit just traced for transformer T¹, and which includes, in addition, wire 63, front contact 64 of relay R¹¹, wires 65 and 66, transformer T⁹, wire 67, and front contact 68 of relay JF to terminal 75 O. Relay JF will have become energized because
- when the train entered section F—G, it caused the release of track relay R⁴, which resulted in the release of relay KF, causing a pickup circuit for relay JF to become closed over back contact 9 of relay KF and front contact 55 of right hand 5 traffic direction relay RF.
- Traffic approaching section G—F from right to left will be governed in an analogous manner by transformers T² and T¹⁰ which are energized over back contact 28 of relay RF, and front contacts of track relays for the intervening track sections. Likewise, a train in section G—F, approaching switch WF, will be governed by coded current supplied to transformer T⁴, the code frequency of this current being usually determined 15 by the condition of the four stick relays MF, SF, LF, and RF at station F, under the control of the despatcher.
- It may be noted that a train entering section F—G from the left, or entering section B—C 20 from the right, will have its supply of code frequency current cut off from the time it enters the section until relay JF or JC picks up. This however is without effect upon the operation of the system, for the reason that the vehicle-carried apparatus for controlling the cab signals is preferably made sufficiently slow acting to bridge such gaps in the trackway control as may occur when a train moves from one block to another, in order to avoid unnecessary breaks 30 in the continuity of the cab signal indications.
- Returning the drawings to the original position, with Fig. 1 on the left, assume that a train moving from left to right and occupying section B—C has received a proceed signal. This train 35 will enter the main line of section C—F, and if relays MF and RF at station F are energized, current of 180 code frequency will be supplied to transformer T⁵ and therefore to track section C—F, so that a proceed cab signal will result. 40 The circuit for transformer T⁵ will be from wire 180 of coder NF, wire 32, front contact 33 of relay KF, wire 34, front contact 35 of relay MF, wire 36, front contact 37 of relay RF, back contact 38 of relay LF, wire 39, and contact 5—4 45 of controller VF to transformer T⁵. Relay KF repeats front contact 40 of track relay R⁴, as well as the front contacts of track relays to the right of point G, and front contact 33 of relay KF therefore insures that a proceed code will 50 not be supplied to transformer T⁵ if section F—G, or a section to the right of point G, is occupied. Should one of such sections be occupied, the resulting deenergization of relay KF will cause an approach code to be supplied to transformer T⁵ 55 over back contact 33 of relay KF and wires 41 and 80.
- If a train is occupying section C—F and the despatcher inadvertently attempts to supply proceed code to transformer T³, by picking up 60 relays MC and RC to permit a following train in section B—C to enter the main line, transformer T³ will be incapable of receiving a proceed code, and will receive an approach code instead. This will result because track relay R⁵, being de- 65 energized under this condition, will deenergize relay PC at front contact 42, and 80 code will be furnished to transformer T³ over a circuit from wire 89 of coder NC, wires 22, 43, and 44, back contact 13 of relay PC, wire 14, front contact 15 of relay MC, wire 16, front contact 17 of relay RC, back contact 18 of relay LC, and wire 19 to transformer T³. The approach code will also be effective at transformer T³, even though section C—F is unoccupied, should the 70 75

despatcher, prior to attempting to supply the proceed code to transformer T^3 , have permitted left hand traffic relay LF to remain energized. The circuit for relay PC would now be inter-

- 5 rupted at back contact 45 of relay LF , and the back contact 13 of relay PC would now impress 80 code, as before, independently of the condition of track relay R^5 .

If, after a train moving from left to right has 10 entered the main section $C-F$, the despatcher wishes to hold the train on the main line, as he might wish to do to permit an opposing train to enter siding $E-D$, he will release relay MF , whereupon, no energizing circuit will exist for 15 transformer T^5 , because front contact 35 of relay MF will be open, and the train will not receive any code, resulting in a stop signal for the main line train. If the despatcher wishes to instruct a train moving on the main line to stop at the right 20 hand end of section $C-F$, he may display an approach signal in this section by energizing either one of the relays MF or SF , maintaining both relays RF and LF deenergized. The circuit for transformer T^5 will now be from wire 80 of coder 25 NF , wire 22, wire 23 and front contact 24 of relay MF , (or wire 73 and front contact 74 of relay SF , if relay SF is picked up instead of relay MF) wires 25 and 75, back contact 37 of relay RF , back contact 38 of relay LF , and wire 39 to trans- 30 former T^5 .

Assume now that after a train has entered the siding $D-E$, as a result of 120 code supplied to transformer T^3 , the despatcher wishes to instruct the train to "leave siding". To do this, he will 35 send out a code to pick up relays RF and SF , whereupon, transformer T^7 will be supplied with 120 code, which, when received by a train occupying the siding will be interpreted to mean "leave siding". The circuit for transformer T^7 starts 40 at wire 120 of coder NF , wire 46, front contact 47 of relay KF , wire 48, front contact 49 of relay SF , wire 50, back contact 51 of relay LF , front contact 52 of relay RF , and wire 53 to transformer T^7 . If the despatcher wishes to hold the 45 train on siding $D-E$, he will fail to pick up relays RF and SF , so that transformer T^7 will not receive current, resulting in a stop indication. Transformer T^8 serves a similar purpose with 50 respect to a train which entered siding $D-E$ from the right.

Because of the shunting effect of the wheels and axles of a locomotive, the code receiving equipment on a locomotive must be placed forward of the first pair of wheels, and this equipment is therefore responsive only to coded current supplied to the rails ahead of the locomotive. For this reason, it is necessary to furnish a code-supplying transformer at each end of a track section, in order that the cab signals will be operative for either direction of traffic movement.

When switch WF is reversed to permit a train to leave siding $D-E$, contact 6-4 of controlled VF becomes closed so that the "leave siding" code being furnished to transformer T^7 will also be supplied to transformer T^5 , to continue the "leave siding" indication until the train enters section $F-G$. At the same time, contact 8-7 of controller VF becomes open, opening the main line rail circuit of section $C-F$, to prevent a 65 train, which might be approaching from the left on section $C-F$, from picking up the 120 code, and receiving the corresponding signal indication. The opening of contact 5-4 of controller VF , which disconnects transformer T^5 from wire 70 39 when switch WF is reversed, insures that

under no condition can a train in section $C-F$, approaching from the left, receive a proceed code with switch WF reversed.

To explain the manner in which a train is governed after leaving section $C-F$, either from the main line or the siding, I shall assume that the train has entered section $F-G$, deenergizing track relay R^4 . Front contact 40 of relay R^4 will be open, and will deenergize relay KF . To permit the train to enter section $F-G$, it was first necessary for relay KF and also relays MF and RF , or SF and RF to have been energized, according as the train approached from the main line, or the siding. In either case, relay RF is picked up, so that when relay KF releases, a pick-up circuit for relay JF becomes closed. This circuit may be traced from one terminal U of a source, back contact 9 of relay KF , wires 10 and 54, front contact 55 of relay RF , wires 56 and 57, and winding of relay JF to the other terminal V of the source. As soon as relay JF picks up, a stick circuit becomes closed over wire 58 and front contact 59, so that relay JF will remain energized as long as relay KF remains released, even though relay RF becomes deenergized in the meantime. If now the drawings are again rearranged so that Fig. 2 occupies a position to the left of Fig. 1, it will be seen that transformer T^9 will now receive code over a circuit starting at a coding device NC , Fig. 1, wires 11 and 27, back contact 28 of relay LC , wire 29, front contact 30 of relay R^3 , wire 63, front contact 64 of track relay R^{11} , wires 65 and 66, transformer T^9 , wire 67, and front contact 68 of relay JF to the other terminal O of the code source. The 180 code frequency will be supplied to transformer T^9 provided sections $G-B$ and $B-C$ in advance are unoccupied, and relay LC at the next station to the right of T^9 is deenergized.

It will be clear from the foregoing that the despatcher must pick up relay RF in order to provide a proceed signal for a train leaving station F and occupying section $F-G$, but that as soon as the train enters section $F-G$ and accepts this signal, the cab signal is removed from control by the despatcher's apparatus at station F and that relay RF may be released without interfering with the cab signal of the departing train.

Assume now that a train is approaching station F from the left and the despatcher wishes to prevent the train from passing point F . As previously explained, the despatcher may energize relay MF or SF only, whereupon a train on the main line would receive an approach signal, which would be interpreted to mean "stop at station F ", while a train on the siding would receive a stop signal. Furthermore, the despatcher may deenergize all stick relays at station F , whereupon a train on the main line would receive a stop signal. If, under any of these three conditions, the train should fail to stop before passing point F , even if wire 63 were supplied with 180 code and relay R^{11} were energized, the released condition of relay JF would cause a stop signal to be displayed in section $F-G$, as a further precaution for holding the train. In the absence of a relay such as JF , track transformer T^9 would repeat only the traffic conditions ahead, and an engineman ignoring or overlooking the stop indication of signal S^5 would receive a proceed signal in section $F-G$, obviously against the wishes of the despatcher.

Although I have shown means for repeating the stop indication into but one section in ad-

vance, which I consider to be sufficient, it will be apparent that such indication could be repeated into several sections, in similar manner. Also, a stop indication in either of the sections 5 G—F or B—C could be repeated into section C—F, for added safety, by similar use of the stick relays JF or JC, directionally selected over the directional relays LF or RC, respectively.

Although I have described certain traffic movements in a given direction only, it will be apparent without further explanation, from the similarity of the control apparatus at stations 10 C and F, that analogous traffic movements in the reverse direction can be similarly controlled.

15 To summarize briefly, I have provided a system of railway traffic control in which cab signals on a locomotive can be controlled at the will of a despatcher located at some distant point, for the purpose of eliminating wayside 20 signals and facilitating traffic movements. I accomplish this result by making use of rail current periodically varied at different frequencies, which frequencies are under the direct control of a despatcher, for controlling traffic movements 25 in accordance with the will of the despatcher, while retaining the safety features necessary for the protection of following and opposing train movements. That is, although track conditions might be such as to make it safe for 30 a train to proceed, the despatcher may display a cab signal indicating that the train should stop, take siding, or proceed on main line. However, if track conditions are such as to make it unsafe for a train to proceed, restrictive signals 35 will be displayed, irrespective of action taken by the despatcher.

Although I have made use of cab signals in illustrating only one embodiment of my invention, it will be understood that my invention 40 can be applied to the control of train governing means of any suitable type. It will be understood also, that although I have described apparatus for controlling but three code frequencies supplied to the trackway, my invention 45 is not limited to the control of this number of codes or to the use of rail current varied in this particular manner, but that the equipment can be expanded to control additional code frequencies, or adapted to control rail current varied 50 in any suitable manner, for performing suitable governing functions upon a train, or supplying any desired information thereto.

Although I have herein shown and described only one form of apparatus embodying my invention, it is understood that various changes 55 and modifications may be made therein within the scope of the appended claims without departing from the spirit and scope of my invention.

60 Having thus described my invention, what I claim is:

1. In combination, a stretch of track including a railway switch, means for supplying the track rails of portions of said stretch with varying current of different characteristics to govern traffic movements over said switch in different directions and routes in accordance with said characteristics, a pair of route stick relays and a pair of traffic direction stick relays, means 65 governed by said relays for controlling the characteristics of said current in accordance with the selective operation of one relay of each of said pairs, and a manually governed device for selectively operating one relay of each of said 70 pairs.

2. Railway traffic controlling apparatus comprising a line circuit connecting a despatcher's office with two remote stations each located at one end of a main track section having a siding associated therewith, an approach section adjacent each end of said main section, means for supplying the track rails of each approach section with alternating current periodically varied at different frequencies for controlling traffic movements into said main section or said 10 siding in accordance with said frequencies, means at each of said stations controlled from the despatcher's office over said line circuit for controlling said frequencies, and means effective when current of a given frequency is being supplied 15 to one of said approach sections for preventing current of the same frequency from being simultaneously supplied to the other approach section.

3. In combination, a stretch of railway track 20 divided into track sections, means for supplying alternating current periodically varied at different frequencies to the track rails of one section, as well as to an adjoining section for controlling traffic movements in said two sections in accordance with said frequencies, a manually operable device for at times controlling the frequency of said periodic variations and for at other times discontinuing the supply of current to said one section, and means governed by traffic moving 25 from said one section into said adjoining section when the current in said one section has been discontinued for preventing the supply of current to said adjoining section.

4. In combination, a despatcher's office and a remote station connected by a line circuit, a stretch of railway track comprising two sections extending in opposite directions from said station, selecting means at said station for supplying current of a selected one of a plurality of 40 possible characters to the track rails of one section or the other, said selecting means including means for selecting the character of current and direction selecting means for determining to which of the two sections the current of selected 45 character is to be supplied, and means controlled from the despatcher's office over said line circuit for controlling said selecting means.

5. In combination, a despatcher's office and a remote station connected by a line circuit, a stretch of railway track comprising two sections extending in opposite directions from said station, selecting means at said station comprising direction selecting means for selectively supplying current to the track rails of one section or 50 the other to govern the indications of a cab signal on a vehicle in the selected section approaching said station, and other selecting means for selectively governing the current supplied to the track rails to determine which one of a plurality 55 of possible indications will be displayed on said vehicle, and means controlled from the despatcher's office over said line circuit for controlling said selecting means.

6. In combination, a despatcher's office and a remote station connected by a line circuit, a stretch of railway track including two sections extending in opposite directions from said station, a plurality of sources of current at said station, selecting means for connecting a selected 65 one of said sources to the track rails of one of said sections or the other for controlling the movement of traffic approaching said station 70 from one direction or the other in said stretch, and means controlled from the despatcher's office 75

over said line circuit for controlling said selecting means.

7. In combination, a dispatcher's office and a remote station connected by a line circuit, a stretch of railway track adjacent said station, a stick relay effective when energized to supply current to the track rails at one end of said section to govern the indications of a cab signal on a vehicle occupying said section, a pickup circuit for energizing said relay including a contact controlled from said dispatcher's office over said line circuit, and a stick circuit for said relay including its own front contact and a contact closed when said section is occupied by a vehicle.
8. In combination, a dispatcher's office and a remote station connected by a line circuit, a stretch of railway track including a first and a second track section adjacent said station, selecting means at said station for at times supplying train governing current to the track rails of said sections, means controlled from the dispatcher's office over said line circuit for controlling said selecting means, and means governed by traffic moving from said first section to said second section for maintaining the supply of train gov-

erning current to the track rails of said second section irrespective of the condition of said selecting means.

9. Railway traffic controlling apparatus comprising a line circuit connecting a dispatcher's office with a plurality of remote stations including one at each end of a section of railway track, a track circuit for said section including a battery connected across the track rails at one end and a track relay connected across the track rails at the other end of said section, a track transformer at one station having its secondary winding in series with said battery, a track transformer at the other station having its secondary winding in multiple with said relay, selecting means at each station controlled from the dispatcher's office over said line circuit, means controlled by each said selecting means for at times supplying alternating current to the primary of the transformer at said station to control the movement of traffic in said section, and means controlled by said track relay for controlling the movement of traffic approaching within a pre-determined distance of said section.

HERBERT A. WALLACE. 25
